UNITED STATES PATENT OFFICE

127,576

DESIGN FOR A WASHING MACHINE AGITATOR

Howard B. Barber, Glenview, Ill., assignor to Montgomery Ward & Co., Incorporated, Chicago, Ill., a corporation of Illinois

Application March 19, 1941, Serial No. 99,708

Term of patent 14 years

To all whom it may concern:

Be it known that I, Howard B. Barber, a citizen of the United States, residing at Glenview, in the county of Cook and State of Illinois, have invented a new, original and ornamental Design for a Washing Machine Agitator, of which the following is a specification, reference being had to the accompanying drawings, forming a part thereof:

In the drawings:

Figure 1 is a side elevational view of a washing machine agitator showing my new design.

Figure 2 is a top plan view thereof;
Figure 3 is a bottom plan view thereof; and Figure 4 is a sectional view thereof on the line 4—4 of Figure 2 looking in the direction of the arrows.

I claim:

The ornamental design for a washing machine agitator, substantially as shown.

HOWARD B. BARBER.
